[57] **CLAIM**

The ornamental design for a handle for hand-held implements, as shown and described.

DESCRIPTION

FIG. 1 is a perspective view of a handle for hand-held implements showing my new design;

FIG. 2 is a top plan view thereof;

FIG. 3 is a front elevational view thereof;

FIG. 4 is a rear elevational view thereof;

FIG. 5 is a side elevational view thereof; and,

FIG. 6 is a bottom plan view thereof.

The broken lines showing of a cheese grater is environmental structure and for illustrative purposes only and forms no part of the claimed design.
